UNITED STATES PATENT OFFICE.

ASBERY T. HARE, OF BAILEYTON, ALABAMA.

GRAIN-GRINDING MILL.

1,296,797.

Specification of Letters Patent. Patented Mar. 11, 1919.

Application filed December 26, 1916. Serial No. 138,934.

To all whom it may concern:

Be it known that I, ASBERY T. HARE, a citizen of the United States of America, residing at Baileyton, in the county of Cullman and State of Alabama, have invented 5 certain new and useful Improvements in Grain-Grinding Mills, of which the following is a specification.

My invention relates to a mill for crushing and grinding corn and other grain.

One distinctive feature of my invention relates to the structure of the frame work of the mill. This is formed in three parts comprising a base or bed and two frames 15 hinged to the ends of this frame and each carrying a vertically disposed grinding stone. These frames are adapted for relative adjustment longitudinally of the frame and also to rock on their hinges to expose 20 the grinding faces of the stones in upright position where they can be most conveniently dressed.

Another feature of my invention relates to the manner in which the stones are adjusted. 25 This I accomplish by drawing the stone carrying frames together by four cross bolts carrying inner adjustable stops and end nuts by means of which the frames can be set with the grinding faces of the stones in 30 contact throughout, after which, by means of a set screw acting on the outer end of the mandrel of the running stone, the latter can be allowed to recede the desired distance from the bed stone. This spacing 35 of the stones is preferably accomplished by means of a spring acting on the mandrel to force it against said set screw.

Another important feature of my invention has for its object to largely increase the 40 capacity of the mill and the quality of the meal or flour without increasing the running speed of the stones or the power required to drive them. This I accomplish by providing in the eye of the bed stone, through 45 which the grain is fed, a crushing means comprising metallic crushing elements which deliver crushed grain to the stones which finish the grinding. I thus rely upon a metallic crusher in combination with grinding stones, as a finishing means, for obtaining 50 such improved results.

Another feature of my invention relates to the means provided for maintaining the balance of the running stone, this being accomplished by recesses formed in the back 55 thereof and carrying radial screws with

weights adjustable thereon. The maintenance of the smooth running of the moving stone is important in preserving uniformity in the grinding of the mill. 60

My invention further comprises the novel detail of construction and arrangements of parts, which in their preferred embodiment only are illustrated in the accompanying drawings, in which:—

Figure 1 shows the mill in side elevation with the parts in operating position.

Fig. 2 is a similar view showing the stone frames opened out.

Fig. 3 is a longitudinal vertical section 70 taken along the center line of the mill.

Fig. 4 is an end elevation looking toward the running stone and with the frame broken away to illustrate the stone balance weights.

Similar reference numerals refer to similar parts throughout the drawings.

In the preferred embodiment of my invention illustrated in the drawings, I show a base in the form of a flat bed plate 1 formed preferably of heavy cross connected 80 timbers having attached along each outer side edge thereof a metal plate or strap 2, in one end of each of which is provided an elongated slot 3 disposed above the level of the frame and in the other end of each of 85 which is provided an opening to receive a pivot pin. The means for directly supporting the running stone comprise two similar frames 4 and 5 which are reversely disposed, the frame 4 comprising on each side 90 bottom members 6 which are adapted to be received between the side plates 2 and to be pivotally and adjustably connected to said plates at their outer ends by a transverse pivot pin 7 inserted through the slots 95 3 and through bearings 8 in the ends of the bottom members 6. This pivot pin is easily removable and provided for the ready detachment for the frame 4, and the pin being free to slide back and forth in the slots 100 3, permits the frame to be adjusted lengthwise of the base 1. The bottom members 6^a of the frame 5 carry bearing members at their outer ends similar to bearings 8 and receive a pivot pin 9 which will have its 105 ends mounted to turn in the holes in the side plates 2 and which is easily removable to provide for the ready detachment of the frame 5.

The frame 5 is braced on each side by up- 110 rights 10 and longitudinal bars 11, which latter bars, when the frame is horizontally

disposed, is of sufficient length to support its upper surface in substantially horizontal position. This frame also comprises a transverse bearing member 12 and parallel with the same is a second bearing member 13 mounted in the uprights 10. These bearing members respectively carry bearings 14 and 15, the latter of which is elongated to receive an adjusting set screw 17 which will engage the outer end of the mandrel 18 on which the driving pulley 19 is keyed between the bearings. The inner end of the mandrel is made fast to the running stone 20, the grinding face of which is dressed in any manner desired. The end of the mandrel extends through the stone and is threaded for detachable connection with an extension mandrel 21 which passes through the eye 22 of the bed or fixed stone 23 and at its outer end is journaled in bearings 24 on a bearing member 13^a of the frame 4. This latter frame comprises members 10^a and 11^a, similar to 10 and 11. The extension mandrel extends beyond the bearing 24 and has a socket in its end which receives a taper stud 25 on a pivoted spring 26 which normally engages the shaft and presses it inwardly. The spring is pivoted to the frame 4 and is free to be swung away from the extension mandrel when desired. This extension mandrel also carries a cam 27, which through rocker elements 28 will shake the feed trough 29 and deliver the grain through an air blast duct 30 into the top opening 31 in the outer end of a concave metallic crusher casing 32 which is rigidly secured in position in the eye of the bed stone, and through the axial center of which passes the main mandrel 18 carrying fixed thereon a metallic cone crusher, both the concave and the cone carrying co-acting burs or equivalent means for effecting a crushing or preliminary grinding of the grain while the same is being delivered through the eye of the bed stone to the grinding faces of the stones.

The stones are adjusted together by means of rods 33 which have their ends threaded to receive stop nuts 35 and fastening nuts 36, the nuts 35 being disposed to engage the adjacent inner faces of the frames 4 and 5 and space them apart while the outer nuts hold the frames together. These tie rods are used two above and two below on each side of the stones. By tightening up on these rods the frames can be adjusted together and locked with the grinding surfaces of the stones in abutment throughout, after which by unscrewing the set screw 17, the spring 26 will tend to separate the stones for the distance determined by the set screw when they will run in true parallelism. They can be easily adjusted nearer or farther apart as may be desired. A casing 37 surrounds the stones when the mill is in

operation and carries a discharge chute 38 which is detachably held in position between the frames.

The bed stone is mounted in a metallic sleeve 39 having longitudinal slots therein through which pass the bolts 40 by means of which the sleeve and bed stone are fixedly secured to the frame 4.

In the rear face of the running stone 20 I provide a plurality of radial slots 41 opening through the perimeter of the stone and having their outer ends closed by a metallic band 42. Metallic plates 43 are inserted in curfs in the stone at the inner ends of the slot 41 and radial screws 44 are made fast at their ends to the plates 43 and band 42. Adjustable balance weights 45 are threaded on the screws 44 and by adjusting these radially the stone may have its running balance preserved. To reduce its friction the stone carries a bushing 46 secured thereto and adapted to receive the mandrel 18.

In operation, having dressed the stones when in the position as shown in Fig. 2, the frames 4 and 5 are swung to the position shown in Fig. 1, the bolts 33 are inserted to draw the frames together, the set screws 17 having been run in to move the mandrel and running stone inwardly. After the frames have been coupled up in the manner described, the spring 26 is applied to the extension mandrel and the screw 17 is turned to permit the stones to separate the desired distance, thereupon the mill is ready for operation. The grain is delivered between the cone and concave to be preliminarily crushed and then passes radially outwardly between the stones, in which passage its grinding is completed.

The convenience of my frame work for taking the mill apart and moving it will be obvious as the base and each frame 4 or 5 can all be separated and handled conveniently, which is a great advantage, particularly in mills for country use.

Having thus described my invention, what I claim as new and desire to secure by Letters Patent, is:—

1. In a vertical grinding mill, a running stone carrying a crushing cone rigid therewith, a bed stone having a concave bur rigid therewith and adapted to receive said cone, a bed plate, a separate frame support for each stone hinged to said bed plate, telescoping mandrels carried by said frame supports and means to permit said stones to be shifted apart sufficiently to disengage the mandrels and permit the cone to clear the concave as the stone frames swing apart on their hinge connections to said bed plate.

2. In a vertical grain grinding mill, the combination with a bed stone and its hinged support, of a running stone and its hinged support, a driving mandrel for the running stone which extends therethrough and into

the eye of the bed stone, an extension mandrel detachably connected to said driving mandrel, bearings for said mandrels, a spring acting to press the extension mandrel toward the running stone, a set screw to limit the movements imparted to the mandrels and running stone by said spring and to hold the stones in predetermined running position, the stone supports being adapted to move apart sufficiently to disconnect the mandrels and permit the stones to swing with their supports to horizontal position.

5 In testimony whereof I affix my signature.

ASBERY T. HARE.
